MAGNETIC CIRCUIT AND METHOD OF
FORMING SAMEHarland E. Wheeler, Elyria, Ohio, assignor to The
General Industries Company, Elyria, Ohio, a
corporation of Ohio

Application January 30, 1940, Serial No. 316,395

2 Claims. (Cl. 175—21)

This invention relates to magnetic circuits and a method of forming such circuits, and more particularly to an improved construction for magnetizable cores of the type used in motors, relays, transformers and other electrical devices.

An object of my invention is to provide an improved construction and method for producing magnet cores in which the core is made in sections so as to facilitate the assembly of the magnet coil or other parts of the device and in which these sections are so formed that they can be readily connected with each other with minimum magnetic reluctance at the point of connection.

Another object of my invention is to provide an improved method and construction for producing magnet coils in which the core is made of complementary sections having cooperating portions shaped to form a locked connection of low magnetic reluctance upon assembly of the sections with each other.

A further object of my invention is to provide an improved construction and method for the production of magnet cores in which complementary core sections are formed of laminations having cooperating portions shaped and arranged to be brought into relatively tight interfitting engagement with each other upon relative swinging of the core sections during assembling thereof.

Still another object of my invention is to provide an improved construction and method for producing magnet cores of the type composed of complementary core sections and in which the core sections have cooperating portions including a pair of locking elements for connecting the sections with each other and a pair of pilot elements adapted to control the relative movement between the core sections during assembly to bring the locking elements into relatively close fitting engagement.

My invention may be further briefly summarized as consisting in certain novel combinations, arrangements of parts and steps of procedure hereinafter described and particularly set out in the appended claims.

In the accompanying sheets of drawings illustrating different embodiments of my invention;

Fig. 1 is a plan view showing an electric motor having a magnet frame or field core constructed according to my invention;

Fig. 2 is a side view of the motor;

Fig. 3 is a plan view showing a pair of complementary core elements or laminations and il-

lustrating my improved construction and method for connecting such core elements;

Fig. 4 is a partial plan view showing another pair of complementary core sections or laminations and illustrating a modified form of connection for assembling such sections;

Fig. 5 is another partial plan view of complementary core sections or laminations and illustrating still another form of connection between such sections; and

Fig. 6 is a plan view similar to Fig. 1 but showing my invention embodied in a four-pole electric motor.

Further reference will now be made to the accompanying drawings for the purpose of describing more in detail my improved method and construction for producing magnet cores, but before proceeding with the detailed description, it will be understood, of course, that the invention is not to be regarded as limited to the particular detailed constructions and devices herein described, because my improvement is applicable to various electrical devices and is susceptible of being carried out in various other ways.

In Figs. 1 and 2 I have shown an electric motor 10 as representing one form of electric device to which my invention may be applied. This motor comprises a magnetizable frame or field core 11 having pole-forming portions 12 and 13 and a rotor 14 operable in the frame or core between such pole-forming portions. The motor shown in this instance is of the shaded-pole type having a magnet coil or field winding 15 mounted on the core 11 and also having pairs of shading coils 16 and 17 mounted on the pole-forming portions 12 and 13. The rotor 14 may be of the usual construction found in motors of this type, that is to say, may comprise a laminated body carrying an annular series of conductor bars 18 and may have a shaft 19 rotatably mounted in suitable bearings 20. These bearings may be carried by plates or bars 21 disposed on opposite sides of the core and mounted thereon by means of screws or posts 22 extending through the core and the spacers 23 and 24.

According to my invention I construct the core 11 by forming the same of two complementary sections 11a and 11b having cooperating portions adapted to form a locked connection 25 of low magnetic reluctance therebetween when the sections are brought into assembled relation to each other. As shown in Fig. 1, the core section 11a may be constructed with the pole portion 12 thereon and with longitudinal and transverse arm portions 26 and 27 which form portions of the

magnetic circuit in the completed device and the latter of which carries the coil 15. The core section 11b may be constructed with the pole portion 13 thereon and may have a longitudinal arm portion 28 which extends substantially parallel with the arm portion 26 and joins the transverse arm portion 27 to complete the magnetic circuit.

The core sections 11a and 11b can be formed of solid bodies of magnetizable material, but preferably, as is common in the electrical art and as shown in this instance, they are formed of a plurality of elements or laminations which may be stamped or otherwise formed from magnetizable sheet material. These laminations are arranged in stacks and may be connected as by means of the rivets 30 extending therethrough to thereby form the core sections 11a and 11b.

To facilitate the connecting of the core sections 11a and 11b with each other during the assembling of the parts of the motor 10, and to insure the formation of the tight connection 25 of low magnetic reluctance between the core sections, I construct the latter with cooperating connecting portions so formed that a mere relative swinging between the sections, as illustrated in Fig. 3, will bring the same into their desired assembled complementary relation and will cause their connecting portions to become interlocked with substantially no air space or gap therebetween. In obtaining this desired result I construct the core sections 11a and 11b, or the laminations thereof, with a pair of cooperating main connecting or locking elements thereon and with a pair of cooperating auxiliary or pilot elements thereon adjacent such main elements. The main connecting or locking elements may be in the form of a tooth-like projection 31 formed on the arm 28 of the section 11b and a recess or socket 32 of similar shape or contour formed in the arm 27 of the core section 11a. The auxiliary or pilot elements may be in the form of a tooth-like projection 33 formed on the core section 11a and a recess or socket 34 of corresponding contour formed in the core section 11b.

These cooperating projections and recesses are so formed and located that by bringing the core section 11b to the broken line position shown in Fig. 3, with the pilot projection 33 seating in the pilot recess 34, the section 11b can be made to pivot or fulcrum on the section 11a and can be swung to its assembled full line position thereby causing the projection 31 to enter the recess 32 and to move into relatively tight fitting or registering engagement with the wall of this recess. It will be seen from the construction and arrangement just described that during this swinging of the core section 11b the pilot elements 33 and 34 remain in sliding or rocking engagement and after the projection 31 has moved into the recess 32, further effort to continue the swinging of the section 11b will wedge the projection 31 more tightly into the recess 32 and will cause a tight metal-to-metal contact to be made particularly along the curved meeting line or face 35. Such metal-to-metal contact and the elimination of air space is desirable particularly along the curved face 35 because it greatly reduces the reluctance of the magnetic circuit. By properly proportioning the core sections, or the laminations forming the same, this desired tight connection can be made to occur at substantially the same time that the pole portions come into abutting engagement at the points 40.

In connection with the formation of the cooperating locking and pilot elements of the core

sections 11a and 11b, it will be observed that the pilot projection 33 forms a portion of the side wall of the locking recess 32 and that it restricts or reduces the opening or passage into this recess so that the locking projection 31 can enter or be withdrawn therefrom only by a swinging movement and hence if the core section 11b is held against reverse relative swinging after it has been moved to its full line position its connection with the core section 11a cannot become loose or disengaged. The projections 31 and 33 can also be regarded as hook-like or tooth-like connecting portions extending in opposite directions in overlapping and interlocking relation with each other.

Although a connection of the form above described for the core sections, and producing the results mentioned, can be formed with cooperating connecting portions of various different contours, Figs. 1 and 3 show the projections and recesses of a specific shape which can be used to advantage and in which the contour of the cooperating projection and recess 33 and 34 is defined mainly by an arc having a radius 36 and the cooperating projection and recess 31 and 32 have a contour defined by arcs struck with the radii 37, 38 and 39 and which merge smoothly into each other.

In assembling the parts constituting the motor 10 the coil 15 is first placed on the arm 27 of the core section 11a and the core section 11b is then brought to the broken-line position shown in Fig. 3 with the pilot projection 33 and recess 34 in engagement with each other. The core section 11b is then swung to its full line position, as explained above, to thereby form the locked connection 25 between the core sections. The rotor 14 is next put into the core opening and the plates 21 are then assembled on the core to complete the mounting of the rotor and to hold the core sections against reverse relative swinging.

In Figs. 4 and 5 I show other pairs of complementary core sections or laminations, similar to the sections 11a and 11b, and also having cooperating portions for connecting them in the same manner and for the same purposes as explained above in connection with Figs. 1 to 3, inclusive. The specific shapes and arrangements of the cooperating portions differ, however, from those of the sections 11a and 11b as will presently be explained. Although the core sections or laminations shown in Figs. 4 and 5 are illustrated only partially, it will be understood, of course, that these core sections or laminations could be of the same shape as the sections 11a and 11b or of some other desired shape, depending upon the character of the electrical device in which they are to be used.

Fig. 4 shows core sections or laminations 41 and 42 in which these interlocking portions comprise a pilot projection 43 and a pilot recess 44 formed respectively on the sections 41 and 42, and a main locking projection 45 and a main locking recess 46 formed respectively on the sections 42 and 41. The projection 43 and its cooperating recess or socket 44 may be formed with an arcuate contour having a radius 47, and the main locking projection 45 and its recess or socket 46 may be formed with an arcuate contour having a radius 48. These projections and recesses are located relative to each other, as shown in Fig. 4, such that the projection 45 resembles a hook or tooth extending toward and part way around the recess 44 so that when the section 41

has been swung from its broken-line position to its full line position to cause the projection 45 to enter the recess 46, the core sections cannot become separated except by reverse relative swinging therebetween. It will also be seen that swinging of the core section 41 to its full line position causes the curved outer face of the projection 45 to be forced or wedged into relatively tight metal-to-metal contact with the curved inner face of the recess 46 to form at this point a connection having substantially no air gap and consequently a low magnetic reluctance.

In Fig. 5 I show core sections or laminations 50 and 51 also having an interlocking connection therebetween formed by cooperating projections and recesses. These projections and recesses include a pilot projection 52 on the section 50 and a pilot recess 53 of similar contour on the section 51, and also include a main locking projection 54 on the section 51 and a main locking recess 55 of similar contour on the core section 50. The projections 52 and 54 are of hook-like or tooth-like form and extend in opposite directions so that an interfitting engagement will be obtained between the recesses and projections when the core section 50 is swung from its broken-line position to its full-line position.

It will be observed that during this swinging of the core section 50 the projection 52 extends into the recess 53 and fulcrums on the projection 54. At the beginning of the swinging movement the fulcrum point is near the outer end of the projection 54 and at the conclusion of the swinging movement the fulcrum point is near the base of the projection 54. It will also be seen that as the swinging of the section 50 takes place, and its fulcrum point shifts down the inclined upper face of the projection 54, this projection will enter the recess 55 and will be forced or wedged into relatively tight metal-to-metal contact with the wall of the recess thereby forming a connection having low magnetic reluctance.

In Fig. 6 of the drawings I show my invention applied to an electric motor 56 of the same type as the motor 10 above described but which is a four-pole motor instead of a two-pole motor. The motor 56 comprises a frame 57 formed of two similar core units 57a and 57b each carrying a magnetizing winding or coil 58. The adjacent ends of the core units 57a and 57b are recessed so that when these parts are brought into abutting relation, a transverse opening 59 is provided for the rotor 60. The core unit 57a carries two of the four poles designated 61 and 62, and the other core unit 57b carries the other two poles 63 and 64. Pairs of shading coils 65 and 66 are mounted on poles of the core units, as shown in the drawings.

The core units 57a and 57b are retained in the abutting relation shown in the drawings by means of plates 67 which are disposed on opposite sides of the core in similar relation to the plates 21 of Fig. 2, but which are of a width to overlie the adjacent end portions of both core units. Screws or posts 68 extending through the plates and core units serve for mounting the plates on the units and enable the plates to connect the core units with each other. The rotor 60 may be mounted for rotation in the opening 59 by means of bearings 69 mounted on the plates 67 and through which the shaft 70 of the rotor extends.

The core units 57a and 57b are each formed of two complemental sections which are connected with each other by a connection or joint 71 similar to the connection 25 illustrated in Figs. 1 and

3 and described above. After the coils 58 and the rotor 60 have been assembled in place these complemental core sections are held against reverse relative swinging by the plates 67.

From the foregoing description and the accompanying drawings, it will now be readily seen that I have provided an improved magnetic circuit or core as well as a novel method of producing the same. Moreover, it will be seen that by reason of my improved construction and method, cores can be formed in two sections to facilitate assembling the coils or other parts of the devices being manufactured and such sections can be readily connected to form a closed magnetic circuit in which the point of connection between the core sections has low magnetic reluctance. It will also be seen that with the cooperating portions of the core sections shaped and arranged as above explained, the connection formed thereby between the core sections will be an interlocking one which cannot readily become loose or disconnected.

While I have illustrated and described my improved core construction and method in a more or less detailed manner, it will be understood, of course, that I do not wish to be limited to the precise details of construction and arrangements of parts herein disclosed, but regard my invention as including such changes and modifications as do not constitute a departure from the spirit of the invention and the scope of the appended claims.

Having thus described my invention, I claim:

1. In a structure of the character described, a laminated core section comprising a plurality of laminations identically shaped so as to form an arm provided with a recess, a second core section comprising a plurality of laminations identically shaped so as to form an arm provided with a projection of a contour corresponding substantially with said recess, an energizing coil carried on the arm of one of said core sections, and cooperating pilot elements provided on said arms shaped to provide a fulcrum for relative swinging movement between the core sections as they approach their assembled position to bring said projection and recess into substantial registering engagement, the projection, recess, and pilot elements being so shaped that final assembly of the sections in a direction lying in a plane parallel to the plane of the laminations is possible only by relative swinging of the sections as they approach their completely assembled position, thereby to form a connection having low magnetic reluctance, and to prevent lateral withdrawal of the projection from its completely assembled position within the recess except by reverse relative swinging.

2. In a magnetic core of the character described, a laminated core section comprising a plurality of superposed laminations each comprising transversely aligned edge portions identically so shaped so as to provide an arm provided with a transverse recess, a second core section comprising a plurality of superposed laminations each comprising transversely aligned edge portions identically so shaped so as to provide an arm provided with a projection whose contour corresponds substantially with that of said recess, and cooperating pilot elements provided on said arms shaped to provide a fulcrum for relative swinging movement between the core sections as they approach their assembled position to bring said projection and recess into substantial registering engagement, the projection, recess, and pilot ele-

ments being so shaped that final assembly of the sections by relative movement thereof in a direction lying in a plane parallel to the plane of the laminations is possible only by relative swinging of the sections as they approach their completely assembled position, thereby to form an abutting pressure contact connection between the said edge portions of the laminations of the two sec-

tions of low magnetic reluctance, and whereby lateral withdrawal of the projection from its completely assembled position within the recess, except by reverse relative swinging, is effectively prevented, and retaining means associated with said core to prevent reverse relative swinging of the sections.

HARLAND E. WHEELER.
